AUTOMATIC FIREARM

Regis Darne, St. Etienne, France

Application June 19, 1935, Serial No. 27,435
In France June 29, 1934

5 Claims.

(Cl. 89—2)

The present invention relates to automatic firearms and its object is to provide a firearm of this kind which is safer to operate, easier to take to pieces, and of higher precision than firearms of the same kind made up to this time.

A first feature of the present invention consists in arranging the parts of the cartridge lifting conveyer in such manner that the cartridges cannot escape accidentally from said conveyer under the effect of the vibrations due to the shock of the action carrier against the rear plate of the breech receiver. Furthermore, according to the invention, this cartridge lifting conveyer is so arranged that, when it reaches its higher position it can move down only when the cartridge is nearly wholly engaged into the chamber, thus preventing any possible distortion of the cartridge when the latter is fed to the barrel.

According to another feature of the present invention, the member intended to limit the displacement of the action carrier toward the front is devised in such manner as to further act as locking means for the cartridge lifting conveyer and also to be able to guide the movable breech in perfectly axial relation with the barrel.

Still another feature of the present invention consists in special means for fixing the feed cam on the action carrier and in the provision of a servo-pawl device intended to render impossible the incident known under the name of "double feed", this incident consisting in a jamming of the cartridges in the feed passage as a result either of a blunder of the person who uses the firearm or of an insufficiently long stroke of the mechanism when the firearm is in action.

Still another feature of the present invention consists in the provision of a connecting rod stopping device adapted to act both ways, this device being intended on the one hand to limit in a yielding manner the displacements of the feed connecting rods which are always brought at the optimum angle into contact with the feed cam, and on the other hand to permit the assembling of the parts of the firearm whatever be the position of the pawl carrying slider.

Still another feature of the present invention consists in providing means which, while ensuring a strong locking of the barrel, permits it to expand without impairing the precision of the arm or disturbing its working.

Finally, still another feature of the present invention consists in the provision of a device which serves to lock the guard in its slideway on the breech receiver and also to yieldingly maintain the safety member in either of its positions "firing", and "safety".

Preferred embodiments of the present invention will be hereinafter described with reference to the accompanying drawings, given merely by way of example, and in which:

Figs. 1 and 2 are a longitudinal sectional view and a transverse sectional view, respectively, illustrating the structure and operation of the cartridge lifting conveyer;

Fig. 3 is a longitudinal view, in section, of the device for fixing the feed cam to the action carrier;

Fig. 4 is a transverse sectional view of the firearm showing the servo-pawl in operation, before the cartridge is in position in the feed passage has been withdrawn from the band of cartridges;

Fig. 5 is a longitudinal vertical sectional view corresponding to Fig. 4;

Fig. 6 is a view similar to Fig. 4, showing the parts in the position they occupy when the cartridge has been withdrawn from the band;

Fig. 7 is a general sectional view showing the whole of the firearm.

The action carrier or frame 1 (Fig. 1), which carries breech block 2, is violently thrown toward the rear by the gases. It first strikes the buffer 3^a and then the closure plate 3. Due to inertia, cartridge 4 has a tendency to slide in the jaws 5^a of conveyer 5 and to escape upwardly therefrom under the action of incline 6^a which cooperates in disengaging the cartridge from said conveyer when said cartridge is engaged into the chamber of the barrel. Several devices were suggested, prior to the present invention, for causing this part 6 to play the part of an obturator.

Breech receiver 7 is provided with two projections 7^a and 7^b and conveyer 5 is provided with a heel or projection 5^c arranged in such manner that the rear end of the spring 8 of the conveyer engages said heel when the conveyer is in its upper position. Accordingly, conveyer 5 is prevented from moving downwardly when the shock of carrier 1 on closure plate 3 occurs. On the other hand, the space between projections 7^a and 7^b is sufficient for permitting the jaws of the conveyer, carrying a cartridge, to pass therebetween, but the jaws cannot move apart from each other, so that cartridge 4 can neither slide toward the rear nor escape upwardly, this being due also to the fact that the jaws 5^a and 5^b of the conveyer are engaged in the groove of the cartridge and are of slightly enveloping shape.

However, it is necessary that the conveyer should be able to move downwardly in the course of its forward movement, so as to be able to catch another cartridge in the feed passage.

For this purpose, when bent member 9, which serves chiefly to guide the front part of the cartridge toward the chamber, comes into contact with the lowering pin 10, this lever is compelled 5 to pivot about its axis 9^a. The heel 9^b of this member 9 then compresses spring 8 downwardly and disengages it from heel 5^c, thus releasing conveyer 5, which can then move downwardly. This arrangement prevents any possibility of the 10 cartridges being distorted when they enter the chamber, since the respective positions of members 9 and 10 are so determined that the disengagement of the cartridge from the conveyer and its insertion into the chamber take place before 15 the conveyer can move down.

Piece 11, when it strikes the lowering pin 10, serves to limit the stroke of the action carrier toward the front. This piece is connected to tongue 12 through a stirrup 13, and this arrangement 20 enables it to undergo without damage the vibrations and shocks to which it is subjected for each stroke of the action carrier. As a matter of fact, piece 11 bears constantly against the action carrier, at 11^a and 11^b, without spindle 12 undergoing any stress, owing to the fact that stirrup 13 permits it to slide with respect thereto until it reaches its optimum position. Furthermore, the movable breech block, which bears 25 against the action carrier, at 1^a, in the rearward direction, and against piece 11, in the frontward direction, is consequently guided in a satisfactory manner in the axial direction with respect to the barrel. Finally, when bolt 2 is removed, it suffices to pivot the whole of the system 11—30 12—13 about spindle 12^a into a position at right angles to the axis of the action carrier in order to easily remove conveyer 5, and also pieces 24 and 6, which are normally attached thereto.

Feed cam 14 (Fig. 3) is fixed on the action 40 carrier 1 by means of two pins 1^b and 1^d which limit its position toward the rear, toward the top and toward the bottom. A stop piece 15, pivoted at 1^c, prevents the cam from moving toward the front when the nose 15^a of said piece 15 is engaged in a notch 14^a of piece 14. This piece 15 is provided with a notch 15^b in which is engaged the nose 8^a of the spring 8 of the conveyer. When, by means of any tool, introduced through a slot provided in piece 14, the nose 15^a of piece 45 15 is depressed out from notch 14^a, cam 14 is free to move toward the front and can thus easily be removed. After the removal of piece 14, piece 15, under the action of spring 8, pivots upwardly about axis 1^c until its heel 15^c comes into contact 50 with pin 1^d. Spring 8 then escapes from notch 15^b. The remounting is effected in the reverse order. It suffices to insert the end 8^a of spring 8 into notch 15^b and then to compress said spring through piece 15, which is depressed by cam 14, 55 the latter being caused to slide toward the rear until the nose 15^a of stop piece 15 engaged notch 14^a. A bent pin, introduced into holes 1^e and 1^f, acts as a safety member which can be placed in position only when cam 14 is well fitted in position. One of the branches of this pin further prevents piston 16 from turning about itself. A hole, provided at 1^g, makes it possible to verify 60 that spring 8 is properly engaged in notch 15^b.

As shown in Figs. 4, 5 and 6, cartridges 50, 50^a, 70 50^b, etc., mounted in links 51, 51^a, 51^b, etc., are fed successively into position in line with the axis of the machine gun, so as to be ready to be caught by the conveyer, the feed movement being imparted to the band of cartridges by pawl 55, 75 pivotally mounted on slider 56, itself controlled

by connecting rods interconnected with the action carrier. It will be readily understood that, if, for some reason, and especially due to an insufficiency of the stroke, the conveyer does not catch the cartridge, it would be impossible to 5 rearm the machine gun if pawl 55 were capable of bringing cartridge 50^a into the position occupied by cartridge 50 while the latter has not yet been extracted from the band by the conveyer. 10

In order to avoid this incident, commonly 10 called "double feed", the action of the pawl is controlled by a member 57 or "servo-pawl". As long as cartridge 50 has not been removed from the band of cartridges, and from the feed passage, by the conveyer, it keeps servo-pawl 57, 15 pivoted at 57^a to slider 56 in lowered position. The nose 57^b of said pawl 57 acts on pawl 55, itself pivoted at 55^a and keeps it in inoperative position.

It should be noted that, in Fig. 5, cartridge 50 20 is suspended in the feed passage between the upper stop member 52 and the lower stop member 53, on the one hand, and fork 54, on the other hand. Cartridge 50 depresses servo-pawl 57 through link 51.

In normal operation of the machine gun, cartridge 50 is withdrawn from the band. Consequently, the link 51 in which said cartridge was carried can now move upwardly (Fig. 6) and ceases to depress servo-pawl 57, which releases 25 pawl 55. The latter is thus in a position to bring a new cartridge 50^a into the place of the cartridge 50 removed from the conveyor.

The gun shown is of the type actuated by gas. The bolting of the movable breech 2 between the back of the gun and the breech receiver 7 in the specification 7^a provided for that purpose as well as the unlocking of the breech 2 are produced by the movements of the carrier mechanism 1. The carrier mechanism is actuated in the usual manner by admitting a portion of the combustion gases so as to act upon the piston 16 located in advance of the carrier mechanism and on the other hand by the reaction action of the spring a. The admission of a portion of the 30 combustion gases is secured through the gas chamber 76 which is in communication with the barrel 75 of the gun and with the tube 78 located in front of the piston 16.

When a shot is fired the entire assembly of 35 the carrier mechanism and the breech block is moved towards the rear under the action of the gas upon the piston 16. At the extreme end the carrier mechanism comes into contact with the element 3^a which is under the action of a spring. 40 The spring a then acts to drive back the assembly towards the front part while raising the cartridge 4 and introducing the same into the chamber of the barrel while at the same time closing the breech. The carrier mechanism 1 comprises 45 a heavy portion b which has the inclined surfaces c and c¹ acting upon correspondingly inclined surfaces upon the breech block in order to cause a bolting thereof during its forward movement and an unlocking upon its rearward 50 movement.

While I have, in the above description, disclosed what I deem to be practical and efficient embodiments of the present invention, it should be well understood that I do not wish to be limited thereto as there might be changes made in the arrangement, disposition and form of the parts without departing from the principle of the present invention as comprehended within 55 the scope of the appended claims.

What I claim is:

1. An automatic firearm comprising a breech block receiver, an action carrier movable in said breech receiver, a barrel fixed to said breech receiver, a barrel chamber for the cartridges, a feed passage, a device for conveying the cartridges from said passage to said chamber, said device comprising a cartridge lifting carrier having pivoted thereto grippers and a cartridge supporting lever, said grippers having external plane surfaces and internal bosses on said receiver cooperating with said plane surfaces preventing spreading of said grippers on the forward stroke of said action carrier. 5
- 10 2. An automatic firearm comprising a breech block receiver, an action carrier movable in said breech receiver, a barrel fixed to said breech receiver, a barrel chamber for the cartridges, a feed passage, a device for conveying the cartridges from said passage to said chamber, said device comprising a cartridge lifting carrier having pivoted thereto grippers and a cartridge supporting lever, said cartridge lifting carrier having a shoulder, a spring engaging said shoulder preventing downward movement of said lifting carrier and means operative by said supporting lever disengaging said spring and permitting downward movement of said lifting carrier. 15
- 15 3. An automatic firearm comprising a breech block receiver, an action carrier movable in said breech receiver, a barrel fixed to said breech receiver, a barrel chamber for the cartridges, a feed passage, a device for conveying the cartridges from said passage to said chamber, said device comprising a cartridge lifting carrier having pivoted thereto grippers and a cartridge supporting lever and a member pivoted to said lifting carrier serving to take the forward shocks to 20 said action carrier and also to lock said lifting carrier in said breech receiver. 25
- 20 4. An automatic firearm comprising a breech block receiver, an action carrier movable in said breech receiver, a barrel fixed to said breech receiver, a barrel chamber for the cartridges, a feed passage, a device for conveying the cartridges from said passage to said chamber, said device comprising a cartridge lifting carrier having pivoted thereto grippers and a cartridge supporting lever and a member pivoted and longitudinally 30 slidable to said lifting carrier serving to take the forward shocks to said action carrier and also to lock said lifting carrier in said breech receiver. 35
- 25 5. An automatic firearm comprising a breech block receiver, an action carrier movable in said breech receiver, a barrel fixed to said breech receiver, a barrel chamber for the cartridges, a feed passage, a device for conveying the cartridges from said passage to said chamber, said device comprising a cartridge lifting carrier having pivoted thereto grippers and a cartridge supporting lever and a member pivoted and longitudinally slidable to said lifting carrier serving to take the forward shocks to said action carrier and also to lock said lifting carrier in said breech receiver. 35

REGIS DARNE. 35
